UNITED STATES PATENT OFFICE.

BAILEY T. MILLIKEN, OF PADUCAH, KENTUCKY.

DESIGN FOR A BED-SPRING.

SPECIFICATION forming part of Design No. 14,242, dated August 28, 1863.

Application filed June 26, 1863. Term of patent 14 years.

To all whom it may concern:

Be it known that I, BAILEY TOWNSEND MILLIKEN, a citizen of the United States, residing at Paducah, in the county of McCracken and State of Kentucky, have invented and produced a new and original Design for Bed-Springs, of which the following is a specification, reference being had to the accompanying drawings, forming part thereof, in which—

10. Figure 1 is a top view of my newly-designed bed-spring, and Fig. 2 is a side elevation of the same.

15. My design consists of a double spring or two coils, A B, formed of a single piece of metal and connected by the reversely-bent part C. The upper convolution of each coil is made polygonal instead of curved, and the connecting part C is formed with the angles D F G H

I K and the curves E J. The lower ends of the coils are formed with the angular loops 20 L M.

What I claim is—

1. The design for a bed-spring, consisting of the coil-spring having the upper polygonal convolution, substantially as shown and de- 25 scribed.

2. The design for a bed-spring, consisting of the double coil-spring and connecting part having the angles D F G H I K and the curves E J, substantially as shown and de- 30 scribed.

BAILEY T. MILLIKEN.
